UNITED STATES PATENT OFFICE.

MILLARD F. FIELD, OF WINTHROP, MASSACHUSETTS, ASSIGNOR TO AMERICAN WARP DRAWING MACHINE COMPANY, A CORPORATION OF MAINE.

WARP-THREAD-SELECTING DEVICE.

1,282,059.

Specification of Letters Patent Patented Oct. 22, 1918.

Application filed January 20, 1916. Serial No. 73,095.

To all whom it may concern:

Be it known that I, MILLARD F. FIELD, a citizen of the United States, and a resident of Winthrop, county of Suffolk, State of Massachusetts, (whose post-office address is 195 Freeport street, Dorchester, Massachusetts,) have invented an Improvement in Warp-Thread-Selecting Devices, of which the following description, in connection with the accompanying drawings, is a specification, like characters on the drawings representing like parts.

This invention relates to devices for selecting warp threads whereby threads may be successively taken from the body of unseparated threads of a warp and positioned for some subsequent operation by thread-engaging devices such, for example, as the drawing in needle of a warp drawing machine.

The invention is herein shown embodied in a warp drawing machine of a well known type, but it has application to machines for acting upon warp threads other than drawing in machines, as well as to warp drawing machines of widely different construction from that herein shown.

The present application is a continuation in part of my prior copending application Serial No. 680,335, filed May 11, 1898; since 30 issued as Patent No. 1,171,388, Feb. 8, 1916; in part of my prior copending application Serial No. 684,201, filed June 23, 1898; and based in part on matter shown in my prior filed application Serial No. 675,100, filed 35 March 25, 1898, and since issued as Patent No. 755,861, March 29, 1904.

The invention will be best understood by reference to the following description when taken in connection with the accompanying 40 illustration of one specific embodiment thereof; while its scope will be more particularly pointed out in the appended claims.

In the drawings:

Figure 1 is a vertical cross sectional view 45 of a warp drawing machine embodying one form of my invention;

Fig. 2 is a rear view of the same, certain parts and portions of the machine being broken away;

Fig. 3 is an elevation, partially in section, upon an enlarged scale, of the warp holding and stretching mechanism, such section being taken on the line 3-3 in Fig. 2 from the right of that figure;

Fig. 4 is a perspective view of the warp

thread selector, herein in the form of a screw together with its immediately connected parts showing the course of the warp threads and the means by which they are acted upon and controlled; 60

Fig. 5 illustrates a modified form of a warp selecting and separating screw;

Fig. 6 shows another modified form of screw selector;

Fig. 7 is a cross section of the screw shown 65 in Fig. 6;

Fig. 8 is a perspective view of the selecting screw shown in Fig. 6 with a slightly different mounting from that shown in Fig. 4;

Fig. 9 is another modified form of warp 70 selecting screw;

Fig. 10 is a cross section taken on the line 10-10 in Fig. 9;

Fig. 11 is a cross section of another modified form of warp selecting screw; and 75

Fig. 12 is a cross sectional view of a pair of clamping bars which may be used in connection with my invention.

Referring to the drawings and to the embodiment of the invention therein illustrated, 1 designates the frame of the machine which supports the tracks 2-2 upon which the carriage 3 travels. The carriage is given a step by step movement by a pawl 4, the latter being actuated from the cam and driving shaft 5 and moving the carriage through the medium of suitable gearing and a pinion 6 which meshes with a track formed on a bar 7 connected with the frame. 80

The bars 8-8 of the harness are supported 90 upon suitable means in the frame, the harness eyes being spaced and positioned by means indicated in Fig. 1 and fully described in Letters Patent No. 755,861, dated March 29, 1904, so that they require no further explanation herein. The reed 9 is loosely supported upon the frame of the machine and 10 is the hook or needle suitably supported and reciprocated by means intermediate of itself and the cam shaft 5. 95

Referring now to the warp thread supports and the thread selecting mechanism, the threads 11 extend up from the warp beam (not shown) and pass between the clamp bars 12, thence partially around a 105 thread contacting and deflecting member 13 and thence between a pair of clamp bars 14. The latter preferably hold the ends of the warp threads frictionally but with a yielding tension and not so firmly as to prevent 110

threads from being drawn out from between the bars without danger of breaking them. The clamp bars 12 preferably hold the threads with an unyielding tension so that 5 the needle will not draw them through those clamps.

To render the clamp bars capable of performing the functions which I have just ascribed to them, I preferably form one of the 10 pairs of bars 12 with a rubber lined groove and the other with a rubber or rubber covered matching tongue. The bars 14 may be formed in the same manner, excepting that I substitute felt or its equivalent for the 15 rubber. In either case the tongue may be a substantial bar in itself so that the tongue and bar may be one piece, as shown at 14. Under this construction the threads, while they are being evened as to length, put 20 under tension and caught and pulled upon by the hook or needle 10 will be immovably held by the clamp bars 12 but will slip from between the bars 14.

The thread contacting member 13 is in the 25 form of a rotatable shaft extending transversely the width or extent of the warp, the warp threads being pressed against the shaft so that the threads held distended by the clamps are deflected, being herein partly 30 wrapped around the shaft so that the sheet of threads lies in two planes forming an acute angle with each other.

The thread selecting mechanism may be provided in a wide variety of constructions 35 or forms, while still embodying the generic features of this invention, but herein the shaft 13 carries at one end (see Fig. 4) thread selecting and separating mechanism in the form of a threaded cylindrical 40 portion 15 of enlarged diameter preceded by suitable devices for tensioning the threads and straightening, disentangling and positioning the same preparatory to their selection by the selecting screw.

45 Preceding the selecting devices on the shaft 13 there is provided means for gradually increasing the tension of the warp threads as they approach the selecting position, such means herein consisting of the 50 frusto-conical and fluted or corrugated part 16.

The screw shaft 13 is mounted upon supports attached to the needle carriage 3, and is herein shown as journaled at one end in a 55 bearing 17, carried by a bracket 18 supported on the needle carriage. At its opposite end it is journaled in a part also on the needle carriage (not herein shown but disclosed in my Patent No. 755,861, dated 60 March 29, 1904) so that it moves with the needle carriage in its step-by-step movement. The shaft is given an intermittent rotary movement in a suitable direction 65 through intermediate means (also disclosed in Patent No. 755,861 but not herein shown)

connected with the shaft of a ratchet wheel 19 (Fig. 1) which is operated upon by a pawl 20, actuated through intermediate connections by a cam on the shaft 5. As relative traverse is effected between the thread 70 clamps and the selecting devices by the step-by-step feeding movement of the carriage hereinbefore referred to, and the threads approach the point of selection, they first pass upon the tapered part of the shaft or part 75 of increasing diameter whereby they are stretched or tensioned and at the same time stroked into parallelism by means of the longitudinal projection or ribs intermediate the flutes. They then pass upon the plain 80 cylindrical part 21 of larger diameter, the rotary movement of which under the tensioned threads assists in straightening them with still greater certainty. There they are positioned one by one for the selecting action 85 by means of the raised shoulder 22 between the cylindrical part 21 and the threaded part 15. The raised shoulder constitutes an abutting wall or formation which is constantly pressed against the edge of the sheet 90 of warp threads and positions the foremost thread or threads for the action of the selector.

The selecting member is herein embodied in the fine wedge-shaped lip, point or edge 95 23 (see Fig. 5) which is formed between the shouldered portion 22 and the angular cut which is produced where the helical groove of the threaded portion 15 breaks through the shoulder. The separator shaft being 100 given an intermittent rotary movement, the selecting lip or edge describes a path which, in the rotation of the shaft, converges toward the sheet of warp threads at the back thereof and gradually cuts across the plane 105 of the threads. This path bearing as it does a definite and fixed relation to the abutting edge permits the selector to cut back of and select the foremost thread positioned by the abutting edge by what may be termed a 110 "slicing" action as distinct from the stabbing or picking action heretofore characteristic of such selectors.

It will be understood that the screw, its shaft, and all of the parts connected therewith will be traversed or moved along co-ordinately with the operation of the drawing-in mechanism, it being desirable that the warp threads should be fed to the warp spacing screw with exactness with respect 115 to all of the conditions effecting or effected by the feed. And it is also to be noted that the portion relating to the feed of the warp threads will be such as always to keep at least one of the threads crowded up against 120 the shoulder or offset 18 of the threaded part of the warp selecting screw so that a warp thread will always be in position to be caught by the thread of the screw whenever 125 its inner selecting lip comes around.

Herein the threads are shown as wrapped about the shaft 13, to have a bearing about the screw of about $\frac{1}{4}$ half or somewhat less than one-half of its circumference, 5 but the extent of this bearing may vary as requirements or circumstances vary.

As indicated in the drawings, the grooved cylindrical portion 15 of the screw is extended for an appreciable length so that the 10 groove is carried along the same for a plurality of turns. A thread is therefore not only selected by the selecting lip of the screw, but is conveyed by the rotary movement of the screw to a position where it can best be 15 taken by the drawing-in needle. By prolonging the length of the groove, an appreciable interval of time is secured during which the screw holds the advancing, but selected and separated threads, under the 20 observation of the operative subsequent to their separation and prior to their being acted upon by the drawing-in needle. Such interval of time may be made to cover a number of successive actions of the selector 25 so that the screw at all times holds preliminarily selected and separated, and subject to the constant inspection of the operative, a series of threads prior to their successive engagement by the drawing-in 30 hook. This enables the operative to check the inaccurate operation of the selector prior to the action of the drawing-in hook.

It is desirable that the warp threads as they arrive at the shoulder 22 of the selecting screw 15 should be presented to the screw at the proper inclination or slope, as it is technically called, that is, in this instance, at the proper angle to the perpendicular face of the said shoulder 22. On account of the 40 varying distances between the several warp threads as they are led up from the warp beam from the screw shaft 13, a frequent variation in the slope of the threads is likely to occur. The best angle of slope for the 45 threads in relation to the shoulder 22 is that which corresponds to the slope of the threads of the screw 15. In order to present each thread at substantially this angle I provide a stop arm 24 upon the bracket 18, which 50 arm projects over the series of threads and has a hooked end 25 which extends down and across the plane in which they lie so that as the drawing in operation proceeds this hook will catch the threads and hold 55 them back to the point at which the hook is adjusted. This point should be a little in advance of the plane of the shoulder 22 at a position which will give the thread next to be selected an angle of slope from the 60 inner surface of the hook 25 to the shoulder 22 substantially the same as the slope of the thread of the screw 15. By this means the engagement of the threads by the selecting lip of the screw 15 will be more accurate 65 and there will be little likelihood of a thread

once taken by the screw being pulled out of it because the slope of the warp threads is too great in front of the shoulder 22, or a second thread snapping over the shoulder because the slope of the warp thread is too little. 70

Each pair of clamp bars 12 and 14 is connected with a section of their carrying frame 26, in the described embodiment of the invention which is so hung or supported that 75 it can move to a limited extent with the clamp bars on a line longitudinally of the latter. In the present case the frame 26 as a whole is supported or hung from journal pins or rods 27 extending horizontally from 80 each end of the frame, which pins run on rollers 28 journaled in a stationary part of the machine frame.

A strap 29 connected at one end to the clamp bar supporting frame passes over a 85 pulley 30 and, by means of weights 31 applied to the other end, tends to move the frame 26 and the clamp bars 12 and 14 carried by it, and as a matter of course, the warp threads engaged by the clamp bars, 90 in the direction of or toward the warp feed screw 15.

The tendency of the weights 31 acting through the medium of the strap 29 on the carriage 26 is to constantly pull the clamp bars 12 and 14 in the direction of the arrow in Fig. 4 as fast as space is provided by the reciprocating needle drawing the warp threads 11 from the hooked end of the arm 24. Consequently, the hooked end 25 of said 100 arm 24 will hold the warp threads and their clamp bars back to exactly the line necessary to keep them from being crowded upon the screw too fast so that the selecting lip of the screw will not take more than one thread at 105 a time in its groove and yet keep the threads fed up to and urged upon the screw with all the stress that is necessary to make sure that the screw will take at least one thread and advance it toward the needle at each rotation of 110 the screw.

The warp being ordinarily of lesser width than the harness, the operation of the machine will ordinarily start with the warp frame moved to the right on its supports as 115 viewed in Fig. 2. When the drawing in is completed or nearly completed, the said frame carrying the clamp bars 12 and 14 will have been moved to the left. The extent of this movement will compensate for the 120 greater normal width of the warp relatively to the width of the harnesses and reed, provision being made at the same time for feeding the warps toward the feed screw with the necessary degree of urgency to enable the screw to take one thread with certainty at each of its rotations.

I have also provided a finger 32 which is adjustably connected with the arm 24 and is of such form and construction that it may 130

bear upon the warps which are being advanced by the feed screw 15 and some of those upon the cylindrical part 21 of the screw shaft, so as to keep the advanced 5 warps from gathering in a bunch by the action thereon of the angular end of the feeler 25 of the arm 24 and also to tend to stroke, as it were, the warp threads down upon the screw and hold them in place. For the latter 10 purpose also a finger 33 (Fig. 4) may be attached to the head 18 and act upon the warps passing up from the clamp 12 to press them inward toward the feed screw. The arm 24 and its adjuncts, as also the finger 33, 15 assist in the exactness of the functions of the screw.

The thread selecting mechanism herein shown may be employed independently of and separately from the automatic compensating feeding mechanism for the warp carriage, and I do not herein claim the latter feature, the same being made the subject of claims in my aforesaid copending application No. 684,201, of which this is a division. 20 The selecting mechanism may be employed either separately from or together with the automatically moved warp support. When the warp carriage is immovable the arm 25 serves solely to regulate the slope at which 25 the warp threads approach the lip of the selector screw. When the warp carriage is given an automatic compensating movement by the means herein shown, the arm 25, in addition to fulfilling that function, serves 30 also as a feeler finger to position or locate the warp support as a whole, and thereby to control its compensating movement. Other and widely different methods of giving the automatic compensating feed to the warp 35 threads may be employed, but, as this constitutes no part of the invention claimed herein, no further reference to them need be made. 40 The frusto-conical part 16 of the feed screw is shown herein (Fig. 4) as fluted or corrugated. This is desirable, though not essential, to assist in stroking the increasingly tensioned threads into parallelism. When the said frusto-conical part is made in fluted form, a portion of the outer edge of 45 one or more of the partitions between the grooves may be constructed as a substantial comb or be slightly notched in order to assist in combing out the crossings or tangles of the warp threads before they approach the parts 21 and 15. The frusto-conical portion may be constructed without the corrugations and still serve the purpose of tensioning the threads, although not with the same effectiveness as when corrugated or 50 provided with a thread stroking formation. Figs. 5 and 8 illustrate a modification of the warp separating screw such as last mentioned, in which the frusto-conical part 16 is not corrugated. 55 It will be understood that those warp

threads which pass around the portion of the screw shaft 13 of smaller diameter will be without substantial tension or under relatively less tension than those undergoing the selecting operation. When they pass up the 70 frusto-conical part 16, however, they will be gradually put under tension until they pass over on the cylindrical part 15, when they will become quite taut.

It is desirable that the tension on the 75 warp threads should be even, and this can best be brought about when the length of the warp threads between the two pairs of clamping bars 12 and 14 is even. To secure this evenness in the length of the portion of warp threads in question, when a warp is put into the machine, I may employ various means, but that herein shown consists of frame sections which support the clamping bars so that one bar may be 80 adjusted to and from the other. The clamping bars 12 are connected with the frame section 34 which is arranged so as to be adjusted up and down on the stationary frame section 35 by means of a pinion 36 85 on the shaft 37 adapted to be rotated by a hand wheel 38 or other means on the said shaft. The said pinion engages a rack 39 on the frame section 34. The clamping bars 14 are supported on the fixed frame section 90 95 34.

The warp threads may be engaged by the clamping bars when they are in the dresser or slasher and they may be engaged so as to make the portions of the threads between the 100 clamps of uniform length, but to make certain of this result, when the warp is put into the drawing machine the clamping bars 12 should be adjusted so that the said portion of warp threads between the clamps 105 will be substantially slack. Then by turning the hand wheel 38 in the proper direction the section 34 of the frame will be moved down with the result of stretching the threads evenly between the two pairs 110 of clamping bars. When this is done the frame section 34 may be secured in a fixed position by any suitable means.

As is herein represented the clamp 14 is supported on swinging arms 40 pivoted on 115 a rod 41 supported in the frame section 35. A spring 42 coiled around the said rod operates upon the arm 40 to press it downward with the clamping bar 14 until the stop 43 on the arm 40 comes into contact with 120 the stationary part 44 of the machine (see Figs. 1, 2 and 3). With this construction the weight of the bar 14 can be made to draw constantly upon the warp threads to assist in keeping them under even tension, 125 and a rigid tension which is undesirable will be avoided.

As has been hereinbefore intimated, when the warp threads are put and maintained under even tension about the screw, as shown 130

in Fig. 4, and a constant relative feed of the warp threads toward the screw is made to compensate for the undue distention of the series of warp threads, the latter can be held or fed up in ~~the~~ against the shoulder 22 of the feed screw so as to insure the taking up of one thread at each rotation of the screw and at the same time the threads will be held back so as not to crowd upon the screw in such manner that there may be liability of the screw catching two or more threads at a time.

The constantly increasing tension put upon the warp threads as they approach the screw part 15 of the screw shaft tends to disentangle or straighten out crossed and otherwise disordered threads and also to put them in exactly proper condition to be controlled and fed one by one to the screw.

The construction of the feed screw and its shaft, as described, relieves the machine from any unnecessary strain by the warp threads and does away with all strain upon the warps by the machine during the operation of drawing in except upon such of the threads as are being at the time operated upon by the screw 15 and the parts of the machine influenced in its operation by those threads.

While the separating and selecting device is shown in its preferred form in Fig. 4, the cylindrical part 21 of the screw may be entirely omitted or may be much shorter than is shown in the drawing, and in fact may be of sufficient length to support a single thread only immediately beside and against the shoulder 22 of the screw threaded portion.

In the construction of the clamp bars 12 and 14 the grooves are made preferably relatively narrow and deep and the tongue thin and wide to fit therein so that the threads will be frictionally held between the sides of the groove and the sides of the tongue and so that the pinching of the threads between the bottom of the tongue and the bottom of the groove or the drawing of the threads about angles between the tongue and groove will not be mainly depended upon as the holding properties of the clamp.

With this construction, when the groove is made to extend from end to end in the part in which it is formed, the sides of the grooves, for all practical purposes, may be swung apart as readily at the ends as in the middle; and also the injurious effect caused by the two clamp bars springing apart at the middle portion only and thus producing uneven friction upon the warp threads at different parts of the clamp will be avoided. This is an important discovery in clamps used in warp drawing and analogous machines.

The finger 33, in addition to bearing

against the warp threads which are being acted upon by the feed screw as described, also operates to hold on to each warp thread after it is drawn in, so that the thread may be more readily knocked out of the needle 70 or hook.

The portion of the thread thus temporarily held back by the finger 33, however, in no wise interferes with the proper accomplishment of the drawing in operation, for, as soon as the drawing in and feeding mechanism, and with them the finger 33, have passed the thread, it is released and may be drawn through the harness eyes and reed when desired.

The purpose of holding the reed loosely in its bearing is to permit of its free, longitudinal movement and thus to adjust it with reference to the traverse of the drawing in device and so to compensate for any irregularities in the distance between the splits of the reed which may have occurred in its construction, or from any other cause.

The appropriate splits of the reed are separated before the advance of the needle by a reed opening lever 45 having the wedge-shaped nose which is adapted to enter between the splits of the reed and press them apart. The said lever being mounted upon a needle carriage, it also acts at the same time to adjust or differentially feed the reed lengthwise in its bearings sufficiently to compensate for any longitudinal displacement of the space between the reed splits from the line of needle movement. The reed opening lever is secured to a rock shaft 46 suitably journaled on the carriage having the depending arm 47 which is operatively engaged by the reciprocatory push rod 48 passing to suitable operating mechanism at the opposite end of the carriage. During operation of the machine the reed opening lever is normally thrown forward by a spring 49 and retracted at a suitable time by the push rod 48. The effect of the construction and arrangement therein shown is to give a compensating feed and adjustment to the reed in relation to the feed of the carriage which supports the drawing in needle, for it is rarely possible to gear the movement of the needle carriage so that the number of reciprocations of the needle will exactly correspond to the number of splits per inch in the reed.

In Fig. 12 I have shown a form of thread clamping bar holding the threads 11 under a yielding tension and adapted to serve in place of the clamp 14 shown in Fig. 4. The clamp shown in Fig. 12 comprises a longitudinally grooved bar 50, and a coöperating bar 51, the latter having a strip 52 of felt cemented in a groove formed in the face of the bar 51, so that the projecting portion of the strip may fit in the groove of the bar 50, clamping the warp threads with the required tension.

site tightness or firmness between the bar 50 and strip 52.

In Figs. 6 and 7 I have shown a modified form of selecting screw wherein there is provided a strip 55 of felt or similar substance set in a groove formed in the screw portion 15 of the selector in such manner that the said felt strip will be brought substantially to the top of the screw when it stops in its 10 intermittent rotary movements. This construction provides enhanced frictional properties to the screw on the line of the felt strip so that in the rotation of the screw the felt will operate with a tendency to stroke or 15 comb out the entanglements or crossed threads, and, when the screw stops, to hold the warp threads against being pulled out of their tension holding clamp and off the screw.

In Figs. 9 and 10 I have shown a modified 20 form of selector wherein the flutes or grooves of the tapered portion 16 of the selector are continued and extended throughout the plain cylindrical portion 21 thereof, one of them being further prolonged through 25 the screw or threaded portion of the selector. This groove may be employed alone, or a 30 felt strip or a metallic sharp edged strip or plate 56 may be set in the longitudinal center of the said groove over which the threads may pass. The ribs or stroking formation of the selector, instead of being formed by flutes or grooves, may be formed as indicated in Fig. 11 by setting suitable 35 strips 57 of metal in the tapered or cylindrical portion of the selector, the longitudinal outer edges of the said strips conforming substantially to the longitudinal preparatory stroking surfaces indicated in Fig. 9.

In Fig. 8 I have indicated a slightly 40 modified mounting for the selector screw. As therein shown, the work of the operative is facilitated by the location of a magnifying glass 58 indicated in dotted lines directly in front of the selector or between the 45 selector and the operative's position. This enables the operative to see the selecting action more distinctly and better enables him to watch the progress of the work and stop the machine if necessary in time to make 50 any needed correction, or remedy any approaching inaccuracy before the trouble reaches the drawing-in needle. In the construction shown in Fig. 8 the arm 24, which 55 regulates the slope of the threads with relation to the selecting screw, has a thread engaging end in the form of a hooked rod 59.

Claims:

1. In a warp thread selecting mechanism, 60 a traversing warp-thread feed-screw provided with an annular shoulder at the end toward the unselected threads, warp-holding devices, and means to hold back the unselected warp-threads to a point in a plane

substantially coincident with the slope of 65 the screw thread at the shoulder.

2. In a warp-drawing machine, a drawing-in needle, a screw automatically movable toward the undrawn warps to engage and feed the warp-threads, warp-holding 70 devices, and an arm to intercept the warp-threads and hold them back to a point in a plane substantially coincident with the thread engaging end of said screw, for the purpose described. 75

3. In a warp-drawing machine, a drawing-in needle, a feed-screw to select and separate the warp-threads, which screw is automatically traversed relatively toward the undrawn warps, warp-holding devices which 80 hold the warp-threads wrapped partially around said screw toward the selecting end of the feed-screw.

4. In a warp-drawing machine, a drawing-in needle, a screw automatically movable toward the undrawn warps to engage 85 and separate the warp-threads; warp-holding devices which hold the warp-threads wrapped partially around said screw, means to give the warp-threads an even tension 90 before they are engaged by said screw, and an arm to intercept the warp-threads and hold them back to a point in a plane substantially coincident with the thread engaging end of the said screw, for the purpose 95 described.

5. In a warp thread selecting mechanism, a feed-screw to select and separate the warp-threads, which screw is automatically movable toward the undrawn warps, means to 100 put the warp-threads under even tension before engagement by said screw, and an arm to intercept the warps as the screw approaches and hold them back to a point in a plane substantially coincident with the 105 thread selecting end of the screw, for the purpose described.

6. In a warp thread selecting mechanism, a warp-thread feed-screw, means to put the 110 warp-threads which are to be successively acted upon by the screw under even tension, and an arm to engage the approaching warp-threads and hold them back to a point in a plane substantially coincident with the 115 thread selecting end of said screw, for the purpose specified.

7. In a warp thread selecting mechanism, a warp-thread feed-screw, means to give an 120 even tension to the threads to be successively acted upon by the screw, devices for guiding the warp-threads and pressing them upon the feed-screw and an arm to engage the warp-threads thereon and hold them back to the selecting end of said screw, for the purpose specified. 125

8. In a machine for acting upon warp threads, warp thread engaging mechanism, a thread-selecting and separating device

adapted, independently of other selecting mechanism, to select warp-threads singly and successively from a compact series, and independently of other mechanism to separate and hold separated a plurality of such threads immediately succeeding each thread presented to the thread engaging mechanism.

9. In a machine for acting upon warp threads, a thread-selecting and separating device consisting of a rotatable shaft and a continuous screw-thread upon a portion thereof, which screw-thread when rotated is adapted, independently of other selecting mechanism, to select and engage threads singly and successively from a compact series upon said shaft, and independently to separate and hold separated a plurality of threads so selected.
10. In a machine for acting upon warp threads, the combination with thread engaging mechanism of a rotating thread-selecting and separating device adapted independently and successively to engage and select the warp-threads singly from a compact series and to hold a plurality of them separated, and thread-clamps which are parallel with the axis of said selecting device and are located in positions to hold the warp-threads partially wrapped about the separating device, and one of which clamps is adapted to release the thread ends successively to the pull of the thread engaging mechanism.
11. In a machine for acting upon warp threads, the combination with thread-engaging mechanism of thread-selecting and separating mechanism adapted independently to select the threads singly and successively from a compact series and independently to separate and hold separated a plurality of threads immediately succeeding each one engaged by the thread engaging mechanism.
12. In a machine for acting upon warp threads, the combination of a shaft provided with a warp-thread selecting and separating screw and thread-holding devices which hold the warp-threads partially wrapped about said shaft and screw.
13. In a machine for acting upon warp threads, a warp-separating screw, and one or more longitudinal ribs upon the shaft adjacent to the screw to serve as means to stroke the warp-threads, for the purpose described.
14. A warp-thread feed-screw for a warp-drawing machine, consisting of a frusto-conical portion, a plain cylindrical portion, and a screw-threaded cylindrical portion, substantially as described.
15. A warp-thread feed-screw for a warp-drawing machine, consisting of a frusto-conical fluted portion, a plain cylindrical portion, a screw-threaded cylindrical por-

tion, and a circumferential shoulder upon the latter next the plain cylindrical portion, the face of which shoulder is in a plane at right angles to the axis of the said cylindrical portions.

16. In a mechanism for separating threads singly and successively from a closely arranged series of unseparated threads, the combination with means to hold the threads distended in substantial parallelism, a rotatable thread-separating means arranged transversely the threads, said means including a rotatable cylindrical thread-straightening member about which the distended threads are partly wrapped and including also a rotary cylindrical selecting and separating member co-axial with and adjacent the straightening member but of greater diameter than the straightening member, thereby to present a thread abutting edge substantially parallel with the threads and against which the edge of the unseparated distended and deflected sheet of threads is adapted to lie, said selecting and separating member having a helical groove formed on its surface and opening through said edge thereby to form at said edge a sharp wedge-shaped lip adapted in its movement to intersect the plane of threads and select the foremost thread by a "slicing" action, means to cause relative traverse between the thread-holding means and the separating means to press the foremost threads against the abutting edge, means to rotate the separating means and means to take the threads from the selecting and separating member.

17. In a mechanism for separating threads singly and successively the combination with means to hold the threads distended, a movable straightening member transverse the threads and against which they are pressed, a rotatable selecting and separating member co-axial with and adjacent said straightening member but of greater diameter thereby to present a thread abutting edge between the two members against which the edge of the sheet of threads is adapted to lie, said selecting and separating member having a helical groove formed on its surface and opening through said edge to form thereat a wedge shaped lip adapted in its movement to cut through the plane of the threads and select the foremost thread by a slicing action, and means to cause relative movement between the threads and the selecting and separating member to press the foremost threads against the abutting edge.

18. In a warp thread selecting mechanism, the combination with means to hold the threads distended, a thread abutting member presenting a wall against which the unseparated, distended threads are adapted

to lie, a selecting member having a path of movement definitely related to the abutting member, said path gradually converging toward and passing through the sheet of threads, means for moving the selecting member to select by a slicing action successive threads positioned by the abutting member, and means for causing relative transverse movement between the warp threads and the abutting member to press the foremost threads thereagainst.

19. In a thread selecting mechanism, the combination with means to hold the threads distended, a movable thread selecting member having an abutting wall against which the edge of the unseparated, distended threads is adapted to lie, said member also having a selecting edge bearing fixed relation to said wall and having a path of movement gradually converging toward and passing through the sheet of threads, means for moving the selecting member to select by a slicing action successive threads positioned by the abutting wall, and means to cause transverse movement between the selecting member and the threads to press the foremost threads against the abutting wall.

20. In a thread selecting mechanism, the combination with means to hold the threads distended, a thread selecting member adapted to turn about an axis, a shouldered portion on said selecting member adapted to lie against the edge of the sheet of threads, a selecting edge also on said member having a path of movement converging toward and passing through the sheet of threads, means to cause relative transverse feeding movement of the selecting member toward the threads, and means to turn the selecting member to select successive threads.

21. In a thread selecting mechanism, the combination with thread-holding means, a rotatable selecting shaft, a shouldered portion against which the threads are adapted to lie to present an abutting wall to the warp threads, said wall having an angular cut to form a wedge-shaped selecting edge movable in a path gradually converging but cutting through the plane of the threads, means for rotating the shaft to select successive threads, and means to cause relative transverse feeding movement between the threads and the selecting shaft.

22. In a thread selecting mechanism, the combination with means to hold the threads distended, a rotatable selecting and separating member having a circumferential shouldered portion to present an abutting edge succeeded by a cylindrical portion, said cylindrical portion having a helical groove forming a wedge-shaped lip in the shouldered portion, said lip in its movement converging toward and passing through the plane of the threads to select the foremost thread by slicing action, means to turn the

cylinder and means to cause relative transverse feeding movement between the threads and the selecting member.

23. In a warp thread selecting mechanism, the combination with thread holding means to hold the threads distended, a thread contacting body arranged transversely the distended threads to press against and deflect the same, a thread abutting wall against which the edge of the sheet of unseparated threads is adapted to lie, a selecting member having a path of movement definitely related to the abutting member and gradually converging toward and passing through the sheet of threads thereby selecting successive threads by a slicing action, means for moving the selecting member to select successive threads and means for causing relative transverse movement between the threads and the abutting member to press the foremost threads thereagainst.

24. In a warp thread selecting mechanism, the combination with warp holding clamps to hold the threads unseparated and distended, a thread contacting body arranged transversely the distended threads to press against the same, means for moving said body lengthwise the threads to draw the threads in parallelism prior to their separation, a selecting member having a path of movement converging toward and cutting across the plate of the threads, means for moving the selecting member to bring the unseparated threads in succession under the direct control thereof and cause said member to select successive threads, and means for causing relative transverse feeding movement between the threads and the selecting member.

25. In a thread selecting mechanism, the combination with thread holding clamps to hold the threads distended, a thread contacting body arranged transversely the distended threads, said body comprising a rotatable member by which the sheet of threads is deflected, an abutting member on said rotatable member against which the edge of the sheet of threads is adapted to lie, means for rotating the rotatable member to draw the threads into parallelism, means for selecting successive threads positioned by the abutting member, and means for causing relative transverse feeding movement between the threads and the abutting member.

26. In a thread selecting mechanism, the combination with means to hold the threads distended, a thread contacting body arranged transversely the distended threads to press against the same, and comprising a shaft about which the threads are partly wrapped, a shouldered portion on said shaft against which the foremost threads are adapted to lie, means for rotating said shaft, means for feeding the same transversely with relation to the sheet of threads and

- selecting means for selecting successive threads positioned against said shoulder.
27. In a thread selecting mechanism, the combination with thread holding means, a cylindrical member adapted to turn about an axis and against which the threads are pressed to be deflected thereby, a shouldered portion on said cylindrical member adapted to lie against the edge of the sheet of threads, a selecting member having a path of movement definitely related to the shouldered portion, said path gradually converging toward and passing through the sheet of threads, and means for turning said cylindrical member.
28. In a thread selecting mechanism, the combination with means to hold the threads, a thread contacting member adapted to lie against and deflect the threads, a shouldered portion on said contacting member adapted to lie against the edge of the sheet of threads, a selecting member having a path of movement definitely related to the shouldered portion, said path gradually converging toward and passing through the sheet of threads, means to move the selecting member to select by a slicing action successive threads positioned by the shouldered portion, and means for causing relative transverse movement between the warp threads 30 and the shouldered portion to press the foremost threads thereagainst.
29. In a thread selecting mechanism the combination with thread holding means for holding a series of threads unseparated, a thread selector and a rotatable thread contacting member arranged transversely the threads and pressed against the same to deflect them, means to cause relative feeding movement between the selector and the threads to bring the unseparated threads progressively under the direct control of the selector, and means for rotating said contacting member to draw the threads into 45 parallelism prior to their selection.
30. In a thread selecting mechanism, the combination with thread selecting means, means to cause relative feeding movement between the selector and the holding means to bring the unseparated threads directly under the control of the selector, rotatable means contacting with the threads to draw the same into parallelism prior to engagement by the selecting means and means also 50 to tension the threads prior to selection.
31. In a thread selecting mechanism, the combination with thread selecting means acting progressively to directly engage and select the threads, thread holding means and rotatable thread contacting means to draw the threads into parallelism and tension them prior to engagement by the selecting means.
32. In a thread selecting mechanism, the combination with thread selecting means 65
- acting progressively to directly engage and select the threads, thread holding means and rotatable thread contacting means to draw the threads into parallelism and tension them prior to engagement by the selecting means.
33. The combination with a thread selector of thread holding means and a rotary tapered shaft to place increasing tension on the threads prior to selection.
34. The combination with thread holding means of thread selecting means and a rotatable thread contacting member having stroking projections for engaging the threads preparatory to separation.
35. The combination with thread holding means of thread selecting means and rotary thread stroking means to engage the threads prior to selection.
36. A thread selector comprising a rotary cylindrical member adapted to press against the threads and a raised abutting shoulder thereon having an angular cut, said member having a helical groove terminating in said cut to convey a selected 85 thread.
37. A thread selecting device comprising a rotatable member having a tapered portion connecting a portion of smaller diameter and a portion of larger diameter, a raised abutting shoulder on said portion of larger diameter and a helical groove also thereon terminating and forming a selecting lip in said abutting shoulder.
38. The combination with thread holding means including a clamp having a yielding tension, separating means and a frusto-conical member contacting with the threads for applying an increasing tension to the threads prior to engagement by the separating means.
39. In a thread selecting mechanism, the combination with thread selecting means of a rotatable thread straightening member about which the threads are partly wrapped and acting to straighten the threads prior to engagement by said selecting means.
40. In a thread selecting mechanism, the combination with a rotatable thread straightening member, a thread abutting formation thereon against which the edge of the sheet of warp threads is pressed and a selecting edge carried by said rotatable member and having a path of movement converging toward and across the sheet of threads to 120 select by a slicing action the successive threads positioned by said abutting formation, means for holding the threads including a clamp having a yielding tension, and means for causing relative feeding movement between the thread holding means and the rotatable member.
41. A warp thread selecting screw consisting of a cylindrical threaded portion provided with a shoulder, a cylindrical plain- 130

surfaced portion adjacent thereto, and a preparatory portion adjacent to the plain cylindrical portion.

42. In a thread selecting mechanism, the combination with a warp selecting screw of warp-thread-stroking means arranged in advance of the selecting screw to engage the threads prior to engagement by the selecting screw.

10 43. In a machine for acting upon warp threads, the combination with a rotary shaft provided with warp thread selecting means of warp holding devices for holding the warp threads partially wrapped around said shaft, and means engaging the threads for pressing them into close contact with the shaft.

20 44. In a machine for acting upon warp threads, the combination with a selecting device, a thread contacting member pressed transversely against the sheet of threads to deflect the same and an arm adapted to press transversely against the threads near the

point of selection to hold them tightly against the deflecting member.

25 45. The combination with warp thread holding means of a selector rotatable about an axis transverse to the warp and thread stroking means movable with the selector.

46. The combination with warp thread holding means of a selector, a rotatable thread contacting member transverse the warp and a strip of frictional material on said contacting member to engage the threads and prepare them for selection.

30 35 47. The combination with a warp thread holding means of a rotatable screw selector and a longitudinal felt strip arranged in the screw for stroking the threads.

40 In testimony whereof, I have signed my name to this specification, in the presence of two subscribing witnesses.

MILLARD F. FIELD.
